PUMP—GEAR AND PISTON COMBINATION
WITH UNLOADINGJohn A. Lauck, Shaker Heights, Ohio, assignor to
Borg-Warner Corporation, Chicago, Ill., a cor-
poration of Illinois

Application April 17, 1948, Serial No. 21,623

5 Claims. (Cl. 103—11)

1

This invention relates to pressure loadable and unloadable pumps, of the character having axially displaceable bushings effective to seal and unseal the side faces of intermeshing gears; and particularly to an improved arrangement for economically and effectively assuring the positive action of the loading and the unloading pressure responsive control means.

This invention is an improvement over that disclosed and claimed in co-pending Lauck application, Serial No. 774,720, filed September 18, 1947, Patent No. 2,505,191, April 25, 1950 and is particularly directed to the novel form and mode of operation of the energizing pump in combination.

It is an object of this invention to provide in an assembly of the present character, a simplified and effective auxiliary pressure generator capable of supplying the relatively small volume of pressure liquid necessary to compensate for leakage and maintain the pilot control valve positively in operated position following the opening thereof, thus avoiding any tendency on the part of the pressure loadable bushings to "hunt."

A more specific object is the provision in combination with a gear pump of the present pressure loadable and unloadable character, of a relatively simple and inexpensive auxiliary single piston energizing pump of very small displacement of a value below that normally practicable of attainment with a gear pump, including forming one of the axially extending journals of the gear pump with a reduced eccentrically disposed shaft and arranging the same to effect the requisite reciprocation of a small piston.

Other objects, advantages, and uses of the invention will become apparent upon reading the following specification taken in connection with the accompanying drawing forming a part thereof and wherein:

Fig. 1 is an axial cross-sectional view taken substantially on the line 1—1 of Fig. 3 bringing out to advantage the novel arrangement of the energizing pump in combination with the main pump;

Fig. 2 is a cross-sectional view taken substantially on the line 2—2 of Fig. 1 bringing out to advantage the arrangement of pilot control valve and pressure relief valve;

Fig. 3 is a transverse cross-sectional view taken substantially on the line 3—3 of Fig. 1 further bringing out to advantage the novel relationship of the energizing pump in combination with the main pump; and

Fig. 4 is a schematic layout view partially in 55 effective to relieve the loading pressure acting

2

section bringing out to advantage the mode of operation.

Referring in greater detail to the figures of the drawing, a plural pump unit or pressure generator unit incorporating a preferred embodiment of the present invention is indicated generally at 10 as comprising a first primary intermeshing gear type pump or pressure generator P—1 and a second auxiliary or energizing pump or pressure generator P—2 in combination therewith.

Pump housing 11 is formed with an inlet 12 and an outlet 13, pump P—1 being contained therein and comprising intermeshing gears 14 and 15 interposed between said inlet and said outlet. Intermeshing gears 14 and 15 include oppositely extending gear journals 14a, 14b, 15a and 15b. Pressure loadable and unloadable end bearing and pumping seal defining bushings indicated generally at S normally engage one side face of gears 14 and 15 in liquid pumping seal relation.

The bushing S has the rear face thereof spaced from the adjacent housing wall and is arranged to receive liquid pressure generated by the gears in contact therewith for the purpose of pressure loading the inner face thereof in pumping seal relation with the adjacent gear side face. For any more detailed understanding of this aspect of the case that may be desired, attention is directed to earlier Roth and Lauck Patent No. 2,420,622, May 13, 1947. Essentially a passage 16 extends along the bushing from adjacent the outlet area of the gear teeth to the back of the bushings while the corresponding passage adjacent the inlet area of the gear teeth is closed by a plug 17.

A second auxiliary or energizing pump or pressure generator P—2 is also contained in housing 11. This second pump in combination and mode of operation forms the subject matter to which this invention is particularly directed.

Essentially, the purpose of this auxiliary or energizing pump P—2 is to maintain a predetermined value of pressure acting on a motor or accumulator to thus assure the dependable operation of the pilot control valve assembly, as well as being effective to make up any small losses due to leakage (as will appear).

A pilot control valve assembly C functions to maintain the loading pressure on bushing S and hence the delivery of pressure liquid by pump P—1 up to a selected value of delivery pressure whereupon pilot control valve C becomes

on bushing S and hence causes the discontinuance of further pressure delivery by primary pump P-1, auxiliary or energizing pump P-2 continuing to operate for the purpose of maintaining the necessary pressure for the purpose of maintaining pilot control valve C in operated condition.

Energizing pump P-2 comprises the formation or provision of a reduced circular cross section portion 14c at the outer portion of journal 14a of gear 14. This reduced portion has an axis offset from the principal axis of journal 14a and is effective when journal 14a is turned to reciprocate a single piston 18. A connecting means 19 is effective to maintain the inner terminal of piston 18 in driven cooperation with reference to an eccentric 20 carried by reduced portion 14c. Connecting means 19 is preferably in the form of a washer-like radially extending portion 19a and an inturned yoke or fork portion 19b embracingly received about a reduced neck 18a of piston 18 effective to confine the inner terminal 18b of piston 18 in driving relation to its eccentric roller 20. Connecting means 19 is preferably confined on the terminal of reduced member 14c by means of a snap ring 19c.

Cylinder 21 for the reception of piston 18 is preferably in the form of an insertable sleeve 21a threadably mounted in a complementary housing bore. Sleeve 21a is formed with a radial inlet port 21b and a radial flange 21c cooperating with a complementary shoulder within the housing for defining the position of the sleeve.

Check valve V-1 is a one-way check valve and may be in the form of an inverted tubular member 22 having one end closed and forming the valve proper cooperating with the outer open terminal of sleeve 21. Coil compression spring 22a is effective to urge valve 22 in the closing direction. Closure member 23 is formed with a complementary bore 23a for guiding reception of valve 22. Inlet passage 24 places inlet port 21b in communication with the inlet line 12 leading from a source of liquid while outlet passage 25 places pump P-2 in communication with outlet line 13 beyond one-way check valve V-2 and in communication with the pressure consumer which may be either a pressure accumulator or a ram type motor such as indicated at M.

Pilot control valve C comprises valve V-3 which is preferably of the conical or disc type having a stem 26 connected with a piston 27 having a cross sectional area corresponding to that of the valve seat engaged by valve V-3 thus completely balancing valve V-3 against any influence from the bushing loading pressure communicated therethrough conduit 29. The outer terminal of piston 27 is placed in communication with the delivery pressure from pump P-1 and P-2 through conduit 28. The cross sectional area of piston 27 and the compression strength of spring 30 are so chosen that valve V-3 is opened upon the occurrence of a delivery pressure of a selected maximum value, to thus cause bushings S to move out of pumping seal engagement with the gear side faces and cause pump P-1 to discontinue further delivery. A valve indicated generally at V-4 may be employed to either return the flow from motor M to the source of pressure or, alternatively, valve V-4 may be arranged to reverse the connection of fluid pressure to motor M in order to produce a power return of the motor in a well known manner.

It will thus appear that the present invention

provides an effective form and arrangement of auxiliary energizing pump in combination, capable of supplying a very small fraction of the volumetric displacement of the primary pump.

For the purpose of providing a suitable maximum pressure relief valve V-5 a one-way ball valve 31 communicates with a complementary port in the outer terminal of the bore receiving piston 27 and is urged in the closing direction by a coil spring 31a.

While the present invention has been disclosed in connection with a specific embodiment thereof it will be understood that this is by way of example rather than by way of limitation and that the invention is to be defined by the appended claims which should be given a scope commensurate with the prior art.

What is claimed is:

1. In a high pressure liquid pump arrangement of the type including a first pump comprising a pair of intermeshing gears and a pressure loadable bearing and pumping seal defining means associated therewith, conduit defining means for applying a part of the output pressure of said pump to pressure load said bearing and pumping seal defining means, and control means effective to relieve the loading pressure on said seal defining means upon the occurrence of a selected value of output pressure, the combination therewith of a second energizing pump comprising a single reciprocable piston having a displacement only a small fraction of the displacement of said first pump, and means rendering the output from said second pump effective to maintain said control valve means operated to continue relieving said loading pressure following the unloading of said first pump.

2. In a high pressure liquid pump assembly of the pressure loadable and unloadable type including, a housing having an inlet thereto and an outlet therefrom; a first pump in said housing comprising a pair of intermeshing gears having axially oppositely extending journals, pressure loadable and unloadable end bearing and pumping seal defining bushing means, means delivering pressure liquid generated by said gears to said bushings for holding the same in pumping seal relation with said gears; a second auxiliary pump in said housing having a displacement that is only a small fraction of the displacement of said first pump and effective to deliver a relatively small volume of liquid to said outlet, said second pump comprising one of said gear journals being formed with a reduced circular cross section portion forming a shaft having an axis offset from the principal axis of the corresponding journal, a single piston, means cooperating between said reduced portion and said piston for effecting reciprocation of said piston upon the rotation of said gear journal; a first one-way check valve between the discharge side of said gears and the discharge from said piston whereby to prevent reverse flow from said piston to said gears; a second one-way check valve, pilot control valve means exclusively responsive to the pressure delivered beyond said check valve effective upon the occurrence of a predetermined value of said pressure to cause the relief of the loading pressure acting on said bushing and hence the unloading of said gear pump, the continued delivery of pressure fluid by said auxiliary piston pump being effective to maintain said pilot valve in open position and to make up any small losses due to leakage.

3. In an arrangement as defined in claim 2, said auxiliary piston motor further comprising a radial bore in said housing, an externally threaded sleeve having a radial flange-like protuberant portion engaging a counterbore in said housing when said sleeve is threadably inserted in said first-named bore, said sleeve being internally formed with a cylindrical bore for the reception of said piston in pumping seal relation thereto, said sleeve having radial inlet ports formed intermediate the terminals thereof and having a one-way spring urged discharge valve cooperating with the outer terminal thereof; and means for causing said piston to be retracted with the return rotation of said reduced journal portion comprising an anti-friction roller embracing said reduced journal portion, a sheet metal retainer clip formed with a first opening therein received in embracing relation about the outer terminal of the reduced shaft portion and an inwardly turned yoke-like portion embracingly engaging a reduced portion of said piston whereby the piston is made to follow the said roller in the retracting direction of movement thereof.

4. In a liquid pressure loadable and unloadable pump assembly including a pair of intermeshing liquid displacing gears having axially oppositely extending journals, pressure loadable and unloadable bushings effective to seal the gear side faces; one of said journals being formed with a reduced eccentrically positioned shaft portion, an anti-friction roller mounted for rotation on said reduced shaft portion, a cylinder containing a piston having means adapted to be engaged by said roller for moving the same radially outwardly, retracting means for said piston for moving the said piston radially inwardly including a sheet-like member having a first opening therein embracing said reduced shaft portion and a second in-turned portion extending generally in

5 a direction parallel to said reduced shaft and engaging said piston means for causing the same to retract said piston bodily as said reduced shaft portion is turned; a one-way check valve disposed between the outlet from said gears and the outlet from said piston to prevent reverse flow from said piston to said gears; a pilot control valve effective upon the delivery of a pressure of predetermined value beyond said check valve 10 for relieving said loading pressure on said bushings, said piston continuing to deliver pressure liquid effective to maintain said pilot valve in operation following said unloading of said gear pump.

15 5. In a pressure loadable pump of the type including a pair of intermeshing gears and pressure loadable bushings adapted to engage one side of said gears in pumping seal relation, conduit defining means for applying a part of the output 20 pressure of said pump to pressure load said bushings, control valve means for relieving the loading pressure on said bushings upon the occurrence of a selected maximum value of output pressure of said pump, a single reciprocable piston type 25 pump associated with said pressure loadable pump, and means for applying the output of said piston type pump to said control valve to maintain said control valve in open position to continue relieving loading pressure following the un- 30 loading of said bushings.
